UNITED STATES PATENT OFFICE.

MELVIN W. PERRY, OF ALGOMA, WISCONSIN.

SPARK-PLUG.

1,362,504.

Specification of Letters Patent. Patented Dec. 14, 1920.

Application filed April 2, 1920. Serial No. 370,742.

To all whom it may concern:

Be it known that I, MELVIN W. PERRY, a citizen of the United States, residing at Algoma, in the county of Kewaunee and State of Wisconsin, have invented certain new and useful Improvements in Spark-Plugs, of which the following is a specification.

My invention relates to certain new and useful improvements in spark plugs, and has for its object to provide a spark plug of the character specified, adapted for use in explosive engines of any character, and wherein a means is provided in connection with the plug for preventing the collection of carbon or other deposit between the points of the electrodes and for maintaining them clean and bright to insure a full sized heavy spark.

With these and other objects in view my invention consists in certain constructions, combinations and arrangements of parts the preferred form of which will be first described in connection with the accompanying drawing and then the invention particularly pointed out in the appended claims.

Referring to the drawings wherein I show several embodiments of my invention, and wherein the same part is designated by the same reference numeral wherever it occurs,

Figure 1 is a perspective view of one form of my improved spark plug;

Fig. 2 is an enlarged view of the lower portion of the plug showing the same construction as that illustrated in Fig. 1;

Fig. 3 is a perspective view of the parts forming my improvement shown in separated relation;

Fig. 4 is a view similar to Fig. 2 with parts in section illustrating a modification; and

Fig. 5 is a detail side view of the movable cleaning member shown in Fig. 4.

Referring particularly to Fig. 1, a complete plug is shown and in which 10 designates the body portion having its lower end reduced and threaded so that it is adapted to be screwed into the spark plug opening of the cylinder. 11 is the packing 45 nut holding the insulated plug 12 in place within the body portion 10. The portion 12 is provided with a longitudinally extending axial opening through which passes the electrode 13. The upper end of the electrode 13 is threaded and the nuts 14 and 15 are threaded on to the electrode above the up-

per end of the insulating plug 12, the nut 14 holding the electrode in place while the nut 15 cooperates with the nut 14 to clamp the battery connection in place. 60

The foregoing construction may be varied as desired and the specific form is shown only for the purpose of illustration.

16 designates a yoke the ends of which are secured in the lower end of the body 65 portion 10, the yoke having its lower central portion formed into a ring 17. In this ring is mounted a movable member 18 formed of suitable insulating material such as porcelain or the like. The movable mem- 70 ber 18 has a cone shaped body portion 19 provided at its upper end with a flange 20, the flange 20 being adapted when the parts are in position to rest upon the upper surface of the ring 17 and support the cone in 75 the position shown in Figs. 1 and 2.

The cone shaped portion is preferably provided with spiral grooves 21 which extend around the periphery of the cone and which at each explosion in the cylinder 80 assist in rotating the cone in the ring 17.

The electrode 13 is provided at its lower end with an enlargement 22 the lower surface of which extends over the flange 20, thus the flange acts to separate the end 22 85 of the electrode 13 from the ring 22. In order to permit a spark to jump from the electrode 22 to the ring 17 I provide the flange 20 with a slot or notch 23.

From the foregoing description it will be 90 seen that the spark can jump from the end 22 of the electrode 13 to the ring 17 carried on the lower end of the part 10 through the slot 23 of the flange 20, and that the pressure developed in the engine cylinder on 95 each upstroke of the piston will act on the conical member 18 to rotate the latter and consequently move the flange 20 around on the ring 17. In the rotation of the member 18 the flange 20 will be lifted so that its 100 upper surface will contact with the under surface 22 of the electrode 13.

It will thus be seen that due to the rotation of the member 18 any carbon, oil or the like, which may be on either the ring 105 17 or the head 22 will be scraped or rubbed off and the members kept bright. Furthermore, the points on the head 22 and the ring 17 between which the spark jumps will be constantly changed.

Referring now to the modification shown in Figs. 4 and 5, the electrode 13 is formed

at its lower end with a head 30, located inside of, and in the same plane with, the ring 17. Between the ring 17 and the head 30 I interpose the flange 31 of the member 32 formed of porcelain or other insulating material, the flange 31 depending from the disk shaped portion 33 of the member. The disk shaft portion 33 is provided with a central opening 34 surrounding electrode 13. The electrode 13 is preferably provided with a spiral groove 35 whereby the pressure of the engine causing the lifting of the member 32 will rotate said member.

The depending flange 31 is provided with a slot 35 through which the spark may jump from the head 30 to the ring 17. It will be seen that the movement of the portion 32 will keep the head 30 and the ring 17 clean in this form of construction in a similar way to that heretofore described in connection with Figs. 1 to 3 inclusive.

Considerable variation of the details as described herein may be resorted to without departure from the spirit of the invention which is to be construed in the light of the following claims:

What I claim as new and desire to secure by Letters Patent is:

1. A spark plug for hydrocarbon engines having one electrode formed into a ring and the other electrode formed into a head, a member formed of insulating material mounted in the ring and adapted to be moved by the pressure in the cylinder, said member being provided with an opening through which the spark may jump from one electrode to the other.

2. A spark plug for hydrocarbon engines having one electrode formed into a ring and

the other electrode formed into a head, a member formed of insulating material mounted in the ring and adapted to be moved by the pressure in the cylinder, said member being provided with a flange extending between the ring and head, said flange being provided with an opening through which the spark may jump from one electrode to the other.

3. A spark plug for hydrocarbon engines having one electrode formed into a ring and the other electrode formed into a head, a member formed of insulating material mounted in the ring and adapted to be moved by the pressure in the cylinder, spiral grooves cut in said member to assist in the rotation thereof, said member being provided with an opening through which the spark may jump from one electrode to the other.

4. A spark plug for hydrocarbon engines having one electrode formed into a ring and the other electrode formed into a head, a member formed with insulating material mounted in the ring and adapted to be moved by pressure in the cylinder, said member comprising a cone shaped body portion adapted to extend through the ring, and a flange extending outwardly from the base of the cone and adapted to rest on top of the ring, said flange being provided with an opening through which the spark may jump from one electrode to the other.

In testimony whereof I affix my signature in the presence of two witnesses.

MELVIN W. PERRY.
